UNITED STATES PATENT OFFICE.

VITO MONTALTO, OF ALLENTOWN, PENNSYLVANIA.

WASHING MACHINE.

Application filed December 18, 1920. Serial No. 431,575.

To all whom it may concern:

Be it known that I, VITO MONTALTO, a former subject of Italy (having declared his intention of becoming a citizen of the United States), residing at Allentown, in the county of Lehigh and State of Pennsylvania, have invented new and useful Improvements in Washing Machines, of which the following is a specification.

10 My invention described herein and being a continuation in part of my application bearing Serial Number 290,514, dated April 16, 1919, relates to a new and useful improvement in washing machines, and has for its 15 object to provide means for extracting a large percentage of the water from the clothes after being washed and elevating them to a point where they may be removed from the washing receptacle without applying 20 the hands thereto.

With these ends in view, this invention consists in the details of construction and combination of elements hereinafter set forth and then specifically designated by the 25 claims.

In order that those skilled in the art to which this invention appertains, may understand how to make and use the same, I will describe its construction in detail, referring 30 by numerals to the accompanying drawings forming a part of this application, in which—

Fig. 1, is a side elevation of my improved washing machine, one side of the casing 35 being removed to clearly show the operating parts within the casing, the pan or washing receptacle and other parts being in section.

Fig. 2, is an elevation taken at right angles to Fig. 1, one end of the casing being 40 removed.

Fig. 3, is a plan view of the machine the cover being removed and a portion of the pan or washing receptacle broken away to show the mechanism beneath the latter.

45 Fig. 4, is a fragmentary plan view of my preferred method of transmitting motion to the oscillating shaft.

Fig. 5, is a fragmentary side elevation thereof.

50 Fig. 6, is a view of a portion of Fig. 5 at right angles thereto.

Fig. 7, is a central, vertical section of the pan or washing receptacle and the mechanism for oscillating the clothes therein, the 55 oscillating shaft being left in section.

Fig. 8, is a section of a portion of the

mechanism shown in Fig. 4 taken at right angles thereto.

Fig. 9, is a section at the line 6—6 of Fig. 5 looking in the direction of the arrow. 60

Fig. 10, is a detail plan view of the lifting board showing the enlarging ring therefor, the latter being partially broken away.

Fig. 11, is a detail, perspective view of the mechanism for elevating the lifting board. 65

Fig. 12, is a fragmentary transverse sectional view of the cover in the region of one of the rollers.

In carrying out my invention as here embodied, 1 represents a rectangular frame or 70 casing for enclosing the operating parts of my improved washing machine and within this casing is suitably mounted the washing receptacle or pan 2 to which is secured the stuffing box 3, 4 representing the packing 75 gland adapted to slide within the stuffing box for compressing the packing therein for the usual purpose.

5 represents a hollow shaft which passes 80 through the stuffing box and is mounted upon the oscillating shaft 6 and connected therewith by the cross pin 7 which is secured in the upper end of the hollow shaft and is adapted to enter into engagement with the forked end 8 of said shaft. 85

9 represents a cap fitted over the upper end of the hollow shaft 5 and this cap has formed therein the slots 10 adapted to pass over the projecting ends of the pin 7 as shown in Fig. 8 and thus cause the cap to 90 oscillate with said hollow shaft. With this cap is formed a wide circular flange 11.

A ring 12 loosely surrounds the lower portion of the cap 9, and has secured therein the posts 13, and these posts project through holes 14 formed in the flange 11 in such manner as to slide freely therethrough and the upper ends of these posts are provided with heads 15 for the purpose hereinafter described. 100

16 represents a bed plate which has an annular recess formed in its underside adapted to fit over the upper end of the cap 9 and this bed plate also has holes 17 formed therethrough for the free passage of the posts 13, the heads 15 of said posts being of sufficient diameter to confine the bed plate upon said posts. The outer diameter of the bed plate may be changed by changing the section 18 thereof which rests upon the 110 flange 11 as shown in Figs. 7 and 10.

From the above description it will be seen

that the oscillations of the shaft 5 will be transmitted to the cap and from it to the bed plate, the bed plate may be raised and lowered through the medium of the hollow shaft 5 and when said bed plate is raised the posts will remain stationary until the heads 15 thereof come in contact with the upper surface of the bed plate when thereafter any further movement of the bed plate will elevate the posts in unison therewith for the purpose hereinafter set forth.

The lower end of the shaft 6 is set in a suitable socket 19 and rests upon the end bearing 20 of such construction as to reduce the friction at this point. Secured to the lower portion of this shaft 6 is a crank arm 21 to which a pitman 22 is attached by a universal joint 23, the opposite end of this pitman being connected by a universal joint 24, to the sprocket wheel 25 which is carried by the shaft 26 journalled in suitable boxes in the casing and this sprocket wheel 25 is geared by the sprocket chain 27 to the sprocket wheel 28 the latter being mounted 25 upon the crank shaft 29.

The crank shaft 29 is journalled in the bearings 30 and 31 secured in the casing and one end of this shaft projects through this casing and is squared as indicated at 32 for the reception of a crank handle 33 shown in dotted lines by which the crank may be revolved by hand when occasion requires.

It is usually preferable to operate such a machine as this by foot power, and I therefore provide the treadle 34 which is pivoted at 35 and is connected by the universal joint 36 to the pitman 37 which is in turn connected by the universal joint 38 to the crank 39. The treadle extends outside of the casing through a suitable opening in the side of said casing.

In order to bring the crank shaft to the starting point a small hand wheel 49 is fixed to the extremity of the same and can be turned by hand.

In order that the machine may be operated by power a suitable motor 40 such as an electric motor is placed within the casing, the belt 41 running over the drive pulley of the motor and over the pulley 42 carried on the crank shaft 29 transmits power from the motor to said crank shaft to steady the movement of this crank shaft a drive wheel 43 is mounted thereon.

From the foregoing description it will be seen that when the crank shaft is revolved either by foot power through the treadle 34, by the motor 40 or by the crank handle 33 the sprocket wheel 25 will be revolved in unison therewith and through the pitman 22 the upright shaft 6 will be oscillated, which oscillations as before described will be transmitted to the bed plate and posts 13.

In order that the bed plate may be raised and lowered for the purpose hereinafter set

forth, I provide a block 44 which has a hole 45 therein of sufficient size to run freely over the shaft 6 and to this block are journalled the pulley wheels 46 and 47 over which runs the cord or cable 48. The ends of this cable are secured to the eyes of the winding drum 50, said cable passing around the pulley wheels 46 and 47 and suspended around pulley wheel 51; by which arrangement it will be seen that when the cable is wound around the drum 50 the block 44 will be elevated and as this block is located immediately beneath the lower end of the hollow shaft 5 the raising of the block will elevate said hollow shaft, causing the latter to slide upward through the stuffing box.

A crank handle 52 is attached to the outer end of the shaft 53 which carries the drum 50 and this shaft also carries a ratchet wheel 54 with which the pawl 55 engages so as to prevent the unwinding of the cable from said drum.

The bracket 56 of the wheel 51 is pivoted as at 57 to permit said wheel to have a to and fro swinging movement to compensate for the movements of the cable.

The casing is provided with a sliding cover 58 having flanges 59 projecting into suitable grooves in the sides of the casing near the top thereof, and having an overhanging flange 60 between which and the cover are journalled the rollers 61 which latter are adapted to travel upon the upper edge of the casing so as to permit said cover to be slid back and forth with but little friction. When closed this cover is substantially vapor tight so as to prevent the steam vapor and odor from the clothes passing into the surrounding atmosphere.

In using my improved washing machine the clothes or other articles to be washed are placed within the pan or receptacle 2 on top of the bed plate and with sufficient amount of hot water containing any desirable washing compound is poured over the clothes and the plate 62 placed upon the top of these clothes which will tend to hold the latter down in place upon the posts 13, now by revolving the crank shaft 29 an oscillating movement will be given to the bed plate as before described, which will cause the clothes to be swung back and forth within the receptacle producing the washing effect, and when this has been continued to a sufficient degree the revolving of the drum 50 in the direction to wind the cable 48 thereon will draw the block 44 upward and with it the hollow shaft 5 which in turn will lift the bed plate carrying the clothes upward therewith and squeezing them against the underside of the plate 62 when the latter comes in contact with the underside of the cover as shown in Fig. 1. This squeezing process will extract a large percentage of the water from the clothes without contami-

120
125
130

nating the hands of the operator and making it unnecessary to use a clothes wringer.

The clothes may be conveniently removed from the machine by first elevating them 5 and squeezing all the water therefrom possible by the process just described and then drawing the water from the receptacle through the faucet 63 after which the clothes may be again lowered sufficiently to remove 10 the plate 62, when by partially opening the cover and again elevating the clothes to approximately a level thereof they may be pushed on to the top of the cover with a paddle or clothes stick. This entirely obviates 15 the necessity of the operator handling the clothes at any time during the washing and wringing process.

By the construction and arrangement of the cable and elevating mechanism for the 20 hollow shaft the bed plate carrying the clothes may be elevated from time to time while it is being oscillated which will squeeze the water from the clothes so that the free dirt will be forced therefrom, and the resubmerging 25 of the clothes will permit relatively fresh water to pass in to the clothes. This will facilitate the washing process.

One of the important features of my improved washing machine is the fact that the 30 oscillating perforated bed plate, posts and extension ring can be readily removed from the tank for cleansing purposes and replaced, at once passing into engagement and adjustment.

35 In Figs. 4, 5 and 6 I have shown the oscillating shaft 6 with a spur gear 70 thereon with which meshes a rack 71, slidably mounted in a bracket 72 carried by the bearing 19 and this rack is connected to the pitman 22 the balance of the mechanism being 40 constructed as hereinbefore described.

Of course I do not wish to be limited to the exact details of construction as herein shown as these may be varied within the 45 limits of the appended claims without departing from the spirit of my invention.

Having thus fully described my invention, what I claim as new and useful is:—

1. In a washing machine, a stationary receptacle, a bed plate, a hollow shaft supporting 50 said bed plate, a block suspended beneath the lower end of the hollow shaft, two pulleys journalled to said block, a cable running over said pulleys and means for taking up and letting out said cable whereby the block will be raised and lowered to 55 raise and lower the hollow shaft.

2. In a washing machine, the combination 60 of a stationary receptacle, a bed plate located within said receptacle, a hollow shaft sup-

porting the bed plate and projecting through the bottom of the receptacle, a lifting member located beneath the lower end of the hollow shaft, two pulleys journalled to said lifting member, a shive wheel carried by the 65 frame of the machine, a drum and a cable the ends of which are attached to said drum, said cable passing around the shive wheel and the two pulleys whereby the lifting member may be raised and lowered to raise 70 and lower the hollow shaft.

3. A washing machine comprising in combination, a receptacle, means for closing the top thereof, a stuffing box in the bottom of said receptacle, a hollow shaft slidably and 75 rotatably mounted in said stuffing box and having one end projecting into the receptacle and the other end outside thereof, a cap on the upper end of said hollow shaft, a bed plate mounted on said cap, a ring, posts 80 carried by said ring and projecting through the cap and bed plate, heads formed on said posts, means for sliding the hollow shaft through the stuffing box to elevate the bed plate and then the ring after the bed plate 85 has been raised sufficiently to engage the post heads, and a plate within the receptacle adapted to be forced against the receptacle by articles on the bed plate when the latter is raised by the elevation of the hollow shaft, 90 for the purpose stated.

4. In a washing machine, the combination of a stationary receptacle, a bed plate located within said receptacle, a shaft supporting 95 said bed plate, a lifting block located beneath the lower end of the shaft, two pulleys journalled to said lifting member, a shive wheel carried by the frame of the machine, a drum, a cable, the ends of which are attached to said drum, said cable passing 100 around the shive wheel and the two pulleys whereby the lifting block may be raised and lowered to raise and lower the shaft, means for revolving the drum and means for holding the same against retrograde movement. 105

5. In a washing machine, the combination with a clothes receptacle and a cover thereon held against a lifting movement, of a bed plate located within the receptacle, means to lift said bed plate in a straight vertical direction and another plate loosely mounted in the receptacle and adapted to rest on top of the clothes in the receptacle, said other plate being moved into contact with and arrested by the receptacle top whereby water will be 115 squeezed from the clothes during the continued upward movement of the bed plate.

In testimony whereof, I have hereunto affixed my signature.

VITO MONTALTO.
